UNITED STATES PATENT OFFICE

150,111

DESIGN FOR A SAFETY KNIFE

Harvey E. Crum, Santa Monica, Calif.

Application January 13, 1947, Serial No. 136,130

Term of patent 14 years

(Cl. D22—3)

To all whom it may concern:

Be it known that I, Harvey E. Crum, a citizen of the United States, residing at Santa Monica, in the county of Los Angeles and State of California, have invented a new, original, and ornamental Design for a Safety Knife, of which the following is a specification, reference being had to the accompanying drawing, forming a part thereof.

Figure 1 is a perspective view of a safety knife showing my new design, the knife being illustrated in closed position.

Figure 2 is a view similar to Figure 1 but showing the knife open ready for use.

Figure 3 is a view in side elevation of the knife as illustrated in Figure 1.

Figure 4 is a view in end elevation from the right in Figure 1.

I claim:

The ornamental design for a safety knife, substantially as shown.

HARVEY E. CRUM.
